UNITED STATES PATENT OFFICE

118,842

DESIGN FOR A ROTARY PUMP BODY OR SIMILAR ARTICLE

Theodore R. Tyler, Minneapolis, Minn., assignor to The Hamilton Corporation, a corporation of Minnesota

Application April 1, 1939, Serial No. 83,976

Term of patent 14 years

To all whom it may concern:

Be it known that I, Theodore R. Tyler, a citizen of the United States, residing at Minneapolis, in the county of Hennepin and State of Minnesota, have invented a new, original, and ornamental Design for a Rotary Pump Body or Similar Article, of which the following is a specification, reference being had to the accompanying drawing, forming part thereof.

In the drawing, Figs. 1 and 2 are top and bottom perspective views, respectively, of a rotary pump body or similar article, showing my new design.

I claim:

The ornamental design for a rotary pump body or similar article, as shown.

THEODORE R. TYLER.
